Patented Aug. 8, 1916.

UNITED STATES PATENT OFFICE.

FERDINAND LENARD, OF CHICAGO, ILLINOIS.

CHAIR.

1,193,802.

Specification of Letters Patent.

Patented Aug. 8, 1916.

Application filed March 13, 1915. Serial No. 14,167.

To all whom it may concern:

Be it known that I, FERDINAND LENARD, a citizen of the United States, residing at Chicago, in the county of Cook and State of Illinois, have invented certain new and useful Improvements in Chairs, of which the following is a specification.

This invention relates to reclining chairs and more particularly to chairs of the Morris type, and has as its object to provide a novel means for holding the back of the chair in positions of angular adjustment, which means will be entirely concealed from view and may be manipulated to permit of adjustment of the back without the necessity of the occupant of the chair arising therefrom.

Primarily the invention aims to provide in a chair of the type mentioned a means for supporting the back in various positions of angular adjustment, which means will be substantial and adapted to securely hold the back and will yet not be exposed to view in such manner as to detract from the appearance of the chair.

In the accompanying drawings: Figure 1 is a vertical sectional view, illustrating one form of the chair embodying the present invention. Fig. 2 is a vertical transverse sectional view on the line 2—2 of Fig. 1.

Corresponding and like parts are referred to in the following description and indicated in all the views of the accompanying drawings by the same reference characters.

In the drawings, the forward legs of the chair are indicated by the numeral 1 and the rear legs by the numeral 2, the seat being indicated at 3 and being of any ordinary or special construction. The rear legs of the chair are connected by a rear cross piece, indicated by the numeral 4. The arm rests of the chair are indicated by the numeral 6 and are supported at their forward ends by the upper ends of the forward legs 1 and at their rear ends by the upper ends of the rear legs 2 and also by spaced uprights 7 between which the pawl and segmental rack elements, which are provided for holding the back at positions of angular adjustment, 50 are housed and operate.

The back of the chair is indicated in general by the numeral 8 and may be of any ordinary construction and the said back is hingedly connected at its rear end, as at 9, 55 to the upper side of the rear cross piece 4. The back 8 preferably includes in its struc-

ture the side members, indicated specifically by the numeral 10, although if desired the back may be of solid formation. To the forward side of each of the side members 10 of the back, or in the event that the back is of solid formation to the forward face thereof at each side there is secured the chordal side of a substantially semi-circular segment 11, one of which segments as will be presently explained is of rack formation. This segment may be of wood or metal and, in the present instance, is relatively thick and projects between the spaced uprights 7 as clearly shown in Fig. 2 of the drawings. 70 By reference to Fig. 1 it will be observed that the chordal side of each segment 11 is secured to the respective side member 10 of the back for a distance substantially equal to the upper half of the length of the said chordal side, so that a portion of the segment extends below the lower edge of the back. As before stated, one of the segments 11 is of rack formation, and this particular segment is clearly shown in Fig. 1 of the drawings and is illustrated as formed in its arcuate forwardly presented edge with a series of sockets 12 of such formation as to define shoulders 13 and inclined walls 14, the sockets being preferably closed at their sides. At this point it will be understood however that if desired the segments 11 may be formed relatively thin and that the one which is of rack formation may have its rack teeth or socket extend the entire width 90 of the arcuate edge thereof. It will further be apparent by reference to Fig. 1, that the arcuate edge of each segment is concentric to the point at which the back is to be angularly adjusted upon its hinges 9, and it will 95 be apparent that as the back is swung upwardly or downwardly and rearwardly, the segments 11 will be correspondingly moved.

In order that the back may be held at various positions of angular adjustment, a pawl is provided for coöperation with that segment which is of the rack formation. The pawl comprises a body portion 15 pivoted at its rear and upper side, as at 16, between the spaced uprights 7, at that side 105 of the chair at which the segmental rack 11 is located. The said portion 15 of the pawl is provided with a forwardly projecting finger 17 which extends beneath the adjacent arm rest 6 and may be engaged for the 110 purpose of swinging the pawl upon its pivot 16. The body portion of the pawl is pro-

vided at its lower rear side with a tooth 18 having a rounded edge portion 19 and a straight or abrupt edge portion 20, the pawl normally resting by gravity with the straight portion of its tooth 18 engaging against the abrupt wall or shoulder 20 of one or another of the sockets 12 in the arcuate edge of the segmental rack, and it will be apparent that by reason of this coöperation of 5 the pawl with the rack, the back of the chair will be held in the position to which it has been adjusted. When it is desired to tilt the back rearwardly, the pawl is rocked upon its pivot so as to move its tooth 18 up out 10 of coöoperative engagement with the rack, as will be readily understood. When it is desired to adjust the back by swinging the same forwardly or toward upright position, this may be accomplished merely by so moving 15 the back upon its hinges, inasmuch as the inclined walls 14 of the sockets 12 will ride over the rounded edge 19 of the tooth 18, and the tooth will automatically successively engage in the sockets as the arcuate edge of the rack rides past the said tooth. It will be understood that the segments 11 may be concealed either by having 20 the uprights 7 extend sufficiently far rearwardly to lie at the opposite sides of the segments even when the back has been swung 25 substantially to the dotted line position shown in Fig. 1 of the drawings, or suitable upholstering may serve to conceal the segments. It will further be observed by reference to Fig. 1, that the forward end of 30 the finger 17 projects but a short distance beyond the forward end of the uprights 7 and is concealed in part by the arm rest beneath which it extends and, if desired, in 35 order to more effectually conceal this finger, 40

the under side of the arm rest may be formed with a recess 21. It will further be understood that while it is herein stated that but one of the segments is of rack formation, both of the segments may be so constructed 45 or formed if desired.

Having thus described the invention, what is claimed as new is:

In a chair of the class described, a frame having a rear cross piece, a back hingedly connected with the said cross piece, the frame including an arm rest, a segment secured to the forward side of the back and having the mid point of its chordal side located substantially in registration with the hinge connecting the back with the cross piece, the arcuate side of the segment being presented forwardly and being provided with a series of rack teeth, and a pawl comprising a plate pivotally mounted at its rear upper corner beneath the arm rest and having its rear edge inclined downwardly and forwardly and provided at its lower end at its said rear edge with a rearwardly extending tooth for coaction with the said rack 60 teeth, the plate being provided with a finger piece projecting forwardly from the upper end of its forward edge, the finger piece being located forwardly beyond the pivot for the plate and the tooth upon the plate being 65 located below the said pivot and the said plate resting by gravity with its tooth in engagement with the said rack teeth.

In testimony whereof I affix my signature in presence of two witnesses.

FERDINAND LENARD. [L. S.]

Witnesses:

PETER KIERDORF,
NICKLOS FEID.
